UNITED STATES PATENT OFFICE.

FRED J. VIEWEG, OF PLAINFIELD, NEW JERSEY.

LOCK.

No. 851,574.

Specification of Letters Patent.

Patented April 23, 1907.

Application filed May 26, 1905. Serial No. 262,337.

To all whom it may concern:

Be it known that I, FRED J. VIEWEG, a citizen of the United States of America, and a resident of Plainfield, Union county, New Jersey, have invented certain new and useful Improvements in Locks, of which the following is a specification.

My invention relates generally to locks, and has more particular reference to the novel construction and arrangement of parts which will be more fully described hereinafter.

In my patent of March 21, 1905, No. 785,132, I show and claim a keyless lock, operative at all times from the inside of the door and having means operable from the outside for rendering the latch mechanism operative or inoperative from the outside. When on the inside of the door, it is possible to render the latch mechanism inoperative 20 but not operative as to the outside.

In my patent of Nov. 28th, 1905, No. 805,687 is shown a keyless lock which can be rendered operative or inoperative as to either side from either side of the door. The latch mechanism, however, is always locked or unlocked as to both sides of the door at any time. In other words, the latch mechanism cannot be independently operated on either side of the door.

In this application, I have shown a keyless lock, operative at all times from the inside of the door, provided with means operable from the outside of the door for rendering the latch mechanism operative or inoperative from that side as desired, and means operable from the inside for rendering the latch mechanism not only inoperative but also operative from the outside. I pause here to remark that when I refer to the "inside" or "outside" of the door either in the specification or claims, I do not mean to use an expression of limitation, but adopt these words merely for convenience in phraseology.

In the prior locks referred to, I employed for the ends sought a collar with a labyrinth of grooves, and a pin engaging therein, the collar and pin being relatively movable. I have found it more convenient in practice to use a disk than a collar, and this application shows the specific means by which I adapt the disk to my keyless lock. Again, in these prior locks, the aim was to connect the parts of a two part spindle, one part of which was in permanent engagement with the latch mechanism, or to move some member which connected the spindle direct to the same.

This has proved unnecessary, as I find it as satisfactory in practice to utilize the combination member itself, as the collar or disk, to actuate the latch mechanism through suitable connections. For determining the relative movement of the collar and pin in these former locks, I employed means located outside of the casing of the lock. In this instance, I use the combination member to unravel its own labyrinth to the initiated,—that is, to indicate through the sense of touch the passage of the pin through its labyrinth of grooves.

In attaining the above general ends, I have made specific improvements which will appear as the specification proceeds.

The accompanying drawings illustrate my invention, and I have used like numerals to designate like parts in the several views. Any mechanic skilled in this art, can readily suggest rearrangement or different construction of parts, and I therefore do not limit myself to the specific arrangement or structures shown. The spirit of my invention will be limited only by the claims.

In the drawings: Figure 1 is a longitudinal sectional view taken on the line 1—1 of Fig. 2. Fig. 2 is a sectional view taken on line 2—2 of Fig. 1. For convenience, in showing its relation to the other parts, the disk, which is in front, is shown in dotted lines. Fig. 3 is a view similar to Fig. 2, looking from the other side of the door with the latch withdrawn. Fig. 4 is a plan view showing the disk with its labyrinth of grooves and its edges indented. Fig. 5 is a detail view partly in section showing the inside knob and connections. Fig. 6 is a detail end view of the knurl piece shown in Fig. 5 in cross section.

In the drawings are shown my lock arranged in the stile 1 of the door. The latch mechanism is contained in the casing 2 provided with the usual face plate 3 through an aperture 4 in which the latch bolt 5 operates.

The latch mechanism is here shown in conventional form and consists essentially of the yoke 6 attached to the latch bolt and connected to the latch arms 7 and 8 moving on the guides 9 and 10 and provided at their rear ends with the bent portions 11 and 12 respectively. The springs 13 and 14 act on the yoke to keep the bolt thrust outwardly or normally in its locked position. The roll back 15 engages with the bent portions of the latch arms in a well known manner.

Properly secured in position by the es-

cutcheon plates 16 and 17 is a two part spindle, the ends of which are adapted to engage with each other. The outer spindle member is designated by the number 18, the inner 5 spindle member by 19, and the knobs 20 and 21 serve to operate the respective spindle members. As previously stated, I use the terms "inside" and "outside" for convenience only, since the parts could of course be 10 reversed and the spindle members applied to the opposite side of the door from that shown in the drawings.

The inner spindle member is at all times in operative relation to the latch mechanism by 15 means of the key 22 formed on its circumference and in permanent engagement with the keyway 23 formed in the collar extension 24 of the roll back.

The outer spindle member is kept in position by means of the lugs 25 and at its inner 20 end is chambered at 26, the walls of the chambered portion 26 being angular in shape to engage with an angular recess formed in the movable member 27, here shown as a disk 25 and whose function will now be described.

I have aimed to supply for the outer spindle member means entirely independent of the inner spindle member adapted to bring the outer spindle member into or out of operative 30 relation to the latch mechanism. While this may be accomplished in various ways, I have here attained my purpose by providing a movable member and means whereby the movable member is capable of actuating the 35 latch mechanism through proper connecting mechanism at a predetermined point in its movement. The movable member is shown in the form of a disk having its face provided with a labyrinth of grooves 28 and the connecting mechanism is preferably in the form 40 of a spring link 29 pivoted to an arm 30 of the roll back. On the side of the link toward the grooves is a pin 30^a adapted to engage with the grooves and to be guided through them 45 by the movement of the disk until the latter is capable of acting upon the pin to actuate the latch mechanism. To enable the latch mechanism to be operated by the rotation of the disk, I provide in the grooves a shoulder 50 31 to which the pin of the link is led when the disk is rotated or turned a variable predetermined number of times and a variable predetermined distance in opposite directions. As will be readily understood from an inspection 55 of Fig. 3, when the pin is in engagement with this shoulder, the further movement of the disk acts on the pin and link to actuate the roll back and thereby withdraw the latch bolt.

60 It is highly desirable to so form the grooves that the pin will be prevented from taking the right course in the grooves when the combination has been improperly operated. Means for accomplishing this result may take 65 various forms. I have here formed in the

grooves inclines 33 and so fashioned the grooves on the face of the disk that they all lead the pin, when the combination is improperly operated, into the groove 34 in which groove it is impossible for the disk and connections to operate the latch mechanism. To counteract any tendency of the inclines of the grooves to throw the pin out from the grooves, I have provided on the opposite side of the link, a projection 35 contacting with the 70 casing and thereby keeping the pin securely in the grooves as it passes through them. It is further necessary, when the pin comes into engagement with the shoulder in the grooves and the rotation of the disk acts upon 80 it to withdraw the latch mechanism, that means be provided for keeping the pin securely against the shoulder. Therefore, I have provided on the casing, a lug 36 onto which the projection on the link slides when 85 it reaches the proper point, thereby holding the pin up to its work against the shoulder.

When the pin of the link is in engagement with the shoulder in the grooves and the latch mechanism therefore operable by the 90 rotation of the disk, means should be provided readily throwing the pin out of engagement with the shoulder in order to make the latch mechanism inoperative as to the outside. For this purpose I have formed on the 95 casing a cam 37 which will move the pin along the face of the shoulder when an extra pressure is exerted on the disk until the pin slips by the corner of the shoulder and through the action of the latch springs is 100 swept through the groove 38 into the groove 34.

The pin, in passing out of engagement with the shoulder, must impart an extra inward motion to the latch bolt equal to the longitudinal movement of the pin, and provision must therefore be made to retract the latch bolt such necessary distance within the face plate. The pin, as it slips off the high portion of the tapers in the grooves has a tendency to produce a slight click sufficient to enable picking of the lock with the aid of a stethoscope. I therefore provide a safety means in the shape of a duplicate spring link, pin and projection numbered 39, 42 and 43 105 respectively, the link being pivoted at 40 to post 41 formed on the casing. This arrangement is a duplicate of the active link 29 and pin 30, and as it travels over the same passage or tapers, will produce the same 110 click and might be called a blind pin or misleader as its only mission is to produce a similar sound to the active pin so that if it is attempted to pick the lock by sound, it will mislead the operator.

115 In my prior inventions referred to in the first part of the specification, I have provided means outside of the casing of the lock for ascertaining the proper operation of the combination,—that is, the passage of the pin 120

through the grooves to such a point that the latch mechanism becomes operative. I have here done away with this auxiliary index or guide, and employ the combination member 5 itself to indicate to the initiated the proper course of the pin through the grooves. This is accomplished by forming in the edge of the disk a series of indents 44 corresponding to the divisions of the labyrinth of grooves. A pawl 45 is adapted to engage with these indents informing the operator by the sense of touch when it has engaged with the same. Means should be provided for forcing the pawl into engagement with the indents as they present themselves. The means which I prefer are shown in Fig. 3 where I have mounted the pawl on the post 46 formed in the casing and provided the pawl with the lever 47 adapted to throw the pawl into the indents. A spring should be provided for actuating the lever to throw the pawl into the indents. In this case I have utilized the latch springs for this purpose as will be understood from an inspection of Fig. 3.

It may be found desirable to bring the spindle members into engagement and to keep them united for the purpose of using the lock as a day latch. Furthermore, it may be desired when on the inside of the door to render the latch mechanism operative from the outside of the door as well as inoperative. That is, assuming the outer spindle member to be out of operative relation to the latch mechanism, it may be found desirable when on the inside of the door, to render the latch mechanism operative or inoperative from the outside without moving the combination member. To that end, the two part spindle has its ends adapted to engage with each other, and means are provided for holding the parts of the spindle normally out of engagement, while other means are adapted to hold them united when the ends are brought into engagement. The engagement of the parts of the spindle is attained by forming a recess 48 in the inner end of the outer spindle, while in a recessed portion 49 of the inner spindle part and seated on the spring 50 therein is the member 51. Both the recess 50 on the outer spindle and the last mentioned member will of course preferably be angular in shape. The spring 50 serves to throw the member quickly into engagement with the recess when the latter and the member are in alinement. Acting against the inside knob to keep the spindle parts normally out of engagement, is the spring 52, here shown seated on the knurl piece 53. The latter is provided in which is formed the groove 55 and extending through the inner spindle member and resting in said groove when the spindle parts are out of engagement is the pin 56.

When it is desired to unite the spindle parts, the inner knob is pushed in against the

action of spring 52 and the knurl piece is turned to keep the knob in its inward position. The member 51 may not be in alinement with recess 48 at the time the inner knob is pushed in, thus forcing it into the inner spindle and causing a compression on spring 50 and this spring will then snap it into engagement with the recess when the alinement is made; that is, immediately after rotating either knob a short distance. Key 22 is in slot 66 provided in member 51 so as to limit movement of the member and keep it out of engagement with recess 48 when the inner knob is in its outward position.

In pushing the knob 21 inward, the pin 56 is forced from the groove 55 in the knurl piece, and by turning the latter the pin rests on the shoulders 57 on each side of the groove and the spindle parts are thereby held in engagement with the latch mechanism which is then operative from the outside of the door through the inner spindle member, whose key is always in engagement with the key-way of the roll back. When, now, it is desired to throw the outer spindle out of operative relation to the latch mechanism, the knurl piece is turned until the groove comes under the pin 56 when the action of the spring 52 will force the member 51 out of engagement with the recess 48. If the combination member has, during this process of uniting and disuniting the spindle members, been out of operative relation to the latch mechanism, the latter will then be left inoperative from the outside except by manipulating the combination.

The operation of the lock is as follows: Assuming the latch mechanism inoperative from the outside, the indexes 58 and 59 on the knob 20 and escutcheon 17 respectively, are brought into alinement when the pin will be located at 60 in the labyrinth of grooves. Then by rotating the disk in opposite directions, the pin is guided through the grooves to the shoulder when the further rotation of the disk acts on the pin to retract the bolt and the lock is open from the outside. When it is desired to lock the door from the outside, the pin may be returned through the labyrinth to the groove 34; or the disk may be further rotated, the cam 37 pushing the pin over the shoulder when the latch spring will cause it to go through the groove 38 to the groove 34 thus throwing it out of connection with the latch mechanism. When it is desired to have the door open at all times, as for use in the daytime, the bolt is converted into a day latch in the manner previously described. The grooves of the disk can be varied either in length or number or divisions, the combination thereby being changeable as desired. In this case I have shown a disk having its grooves formed into twelve divisions as indicated by the notches on the disk best seen in Figs. 3 and 4 and the combi-

nation is 3, 9, 3. *i.e.* the pin being at the starting point 60 is led through the grooves to 61, where, if the disk be turned too far, the pin slips over the tapered portion 62 and passes into the groove 34, it being impossible to return it to 61 without bringing it back to the starting point. From 61 the pin is moved to 63, then to 64, when the motion being reversed, the pin is brought to the shoulder at 65 and the latch mechanism is operative from the outside. At each point where the direction of rotation should be changed, the pin is prevented by the inclines from taking the right course if moved too far, and the combination therefore improperly operated. The combination of grooves can of course be changed and the disk can therefore be moved a variable predetermined number of times and a variable predetermined distance in opposite directions to bring the pin to the shoulder. Of course cams having different combinations can be readily substituted. The first number of the combination can be changed by removing the outer knob with the spindle and replacing it, merely changing its position in relation to the angular hole in the combination disk. In case the combination is on, it can be thrown out from the inside by pressing the inner knob and spindle into connection with the outer one and upon rotating it, the pin will be forced out of connection with the latch mechanism, as previously described.

It will be seen from an inspection of Fig. 4 that the passages 62, 62^a and 62^b constitute misleading passages, whereby when the cam disk is improperly operated in either direction the link or other member will be caused to take a course which will lead it to the starting groove 34 in less than one revolution of the disk without reversing the motion.

What is claimed is:

1. In a lock in combination: latch mechanism, a movable member, a knob and connections adapted to move the member, mechanism pivoted on the latch mechanism and connecting the member therewith, the member being adapted to guide the connecting mechanism to a point where the movable member is capable of acting upon it to actuate the latch mechanism.

2. In a lock in combination: latch mechanism, a movable member, a knob and connections adapted to move the member, mechanism pivoted on the latch mechanism and connecting the member therewith, the member being adapted when turned a variable predetermined number of times and a variable predetermined distance in opposite directions to guide the connecting mechanism to a point where the movable member is capable of acting upon it to actuate the latch mechanism.

3. In a lock in combination: latch mechanism, a movable member, a knob and con-

nnections adapted to move the member, a link pivoted on the latch mechanism and connecting the latch mechanism and member, the latter being adapted to guide the link to a point where the movable member is capable of acting upon it to actuate the latch mechanism.

4. In a lock in combination: latch mechanism, a movable member, a knob and connections adapted to move the member, a link pivoted on the latch mechanism and connecting the latch mechanism and member, the latter being adapted when turned a variable predetermined number of times and a variable predetermined distance in opposite directions to guide the link to a point where the movable member is capable of acting upon it to actuate the latch mechanism.

5. In a lock in combination: latch mechanism, a movable member, a knob and connections adapted to move a member, a link pivoted on the latch mechanism and connecting the latch mechanism, and member and in engagement with the movable member, and means carried by the latter adapted to act on the link to actuate the latch mechanism at a predetermined point in the movement of a movable member.

6. In a lock in combination: latch mechanism, a movable member, a knob and connections adapted to move the member, a link pivoted on the latch mechanism and connecting the latch mechanism and member and in engagement with the movable member, and means carried by the latter adapted when the movable member is turned a variable predetermined number of times and a variable predetermined distance in opposite directions to act on the link to actuate the latch mechanism at a predetermined point in the movement of a movable member.

7. In a lock in combination: latch mechanism, a movable member, a knob and connections adapted to move the member, a link pivoted on the latch mechanism, and connecting the latch mechanism and member, a pin on the link in engagement with the movable member, and a shoulder formed in the latter adapted to act on the pin to actuate the latch mechanism at a predetermined point in the movement of the movable member.

8. In a lock in combination: latch mechanism, a movable member, a knob and connections adapted to move the member, a link pivoted on the latch mechanism and connecting the latch mechanism and member, a pin on the link in engagement with the movable member, and a shoulder formed in the latter adapted when the movable member is turned a variable predetermined number of times and a variable predetermined distance in opposite directions to act on the pin to actuate the latch mechanism at a pre-

determined point in the movement of the movable member.

9. In a lock in combination: latch mechanism, a movable member provided with a labyrinth of grooves, a knob and connections adapted to move the member, a link pivoted on the latch mechanism and connecting the latch mechanism and member, a pin on the link engaging with said grooves, means carried by the movable member adapted to act on the pin to actuate the latch mechanism when the member is moved a variable predetermined number of times and a variable predetermined distance in opposite directions to lead the pin through the grooves to said means.

10. In a lock in combination: latch mechanism, a movable member provided with a labyrinth of grooves, a knob and connections adapted to move the member, a link pivoted on the latch mechanism and connecting the latch mechanism and member, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder.

11. In a lock in combination: latch mechanism, a movable member provided with a labyrinth of grooves, a knob and connections adapted to move the member, a link connected to the latch mechanism, a pin on the link engaging with said grooves, means carried by the movable member adapted to act on the pin to actuate the latch mechanism when the member is moved a variable predetermined number of times and a variable predetermined distance in opposite directions to lead the pin through the grooves to said means, and means adapted to prevent the pin from taking the right course in the grooves when the combination is not properly operated.

12. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, and means adapted to prevent the pin from taking the right course in the grooves when the combination is not properly operated.

13. In a lock in combination: latch mechanism, a movable member provided with a labyrinth of grooves, a knob and connections adapted to move the member, a link connected to the latch mechanism, a pin on the

link engaging with said grooves, means carried by the movable member adapted to act on the pin to actuate the latch mechanism when the member is moved a variable predetermined number of times and a variable predetermined distance in opposite directions to lead the pin through the grooves to said means, and inclines formed in said grooves adapted to prevent the pin from taking the right course in the grooves when the combination is not properly operated.

14. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, and inclines formed in said grooves adapted to prevent the pin from taking the right course in the grooves when the combination is not properly operated.

15. In a lock in combination: latch mechanism, a movable member provided with a labyrinth of grooves, a knob and connections adapted to move the member, a link pivoted on the latch mechanism and connecting the latch mechanism and member, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, and means adapted to hold the pin against the shoulder when the latter is acting upon it.

16. In a lock in combination: latch mechanism, a movable member provided with a labyrinth of grooves, a knob and connections adapted to move the member, a link connected to the latch mechanism, a pin on the link engaging with said grooves, means carried by the movable member adapted to act on the pin to actuate the latch mechanism when the member is moved a variable predetermined number of times and a variable predetermined distance in opposite directions to lead the pin through the grooves to said means, means adapted to prevent the pin from taking the right course in the grooves when the combination is not properly operated, and means adapted to keep the pin in the grooves.

17. In a lock in combination: latch mechanism, a movable member provided with a labyrinth of grooves, a knob and connections adapted to move the member, a link connected to the latch mechanism, a pin on the link

engaging with said grooves, means carried by the movable member adapted to act on the pin to actuate the latch mechanism when the member is moved a variable predetermined number of times and a variable predetermined distance in opposite directions to lead the pin through the grooves to said means, inclines formed in said grooves adapted to prevent the pin from taking the right course in the grooves when the combination is not properly operated, and means adapted to keep the pin in the grooves.

18. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, inclines formed in said grooves adapted to prevent the pin from taking the right course in the grooves when the combination is not properly operated, means adapted to hold the pin against the shoulder when the latter is acting upon it, and means adapted to hold the pin in the grooves.

19. In a lock in combination: latch mechanism, a rotatable disk provided with a labyrinth of grooves, a knob and connections adapted to move the disk, a link connected to the latch mechanism, a pin on the link engaging with said grooves, a shoulder formed in said grooves adapted to act on the pin to actuate the latch mechanism when the disk is rotated a variable predetermined number of times and a variable predetermined distance in opposite directions to lead the pin through the grooves to said shoulder, a lug formed on the casing adapted to hold the pin against the shoulder when the latter is acting upon it, and a projection on the opposite side of the link adapted to contact with the casing and to keep the pin in the grooves.

20. In a lock in combination: latch mechanism, a rotatable disk provided with a labyrinth of grooves, a knob and connections adapted to move the disk, a link connected to the latch mechanism, a pin on the link engaging with said grooves, a shoulder formed in said grooves adapted to act on the pin to actuate the latch mechanism when the disk is rotated a variable predetermined number of times and a variable predetermined distance in opposite directions to lead the pin through the grooves to said shoulder, and a projection on the opposite side of the link adapted to contact with the casing and to keep the pin in the grooves.

21. In a lock in combination: latch mechanism, a movable member, a knob and con-

nctions adapted to move the member, a link connected to the latch mechanism, a pin on the link in engagement with the movable member, a shoulder formed in the latter adapted to act on the pin to actuate the latch mechanism at a predetermined point in the movement of the movable member, and means adapted to throw the pin out of active engagement with the shoulder.

22. In a lock in combination: latch mechanism, a movable member, a knob and connections adapted to move the member, a link connected to the latch mechanism, a pin on the link in engagement with the movable member, a shoulder formed in the latter adapted when the movable member is turned a variable predetermined number of times and a variable predetermined distance in opposite directions to act on the pin to actuate the latch mechanism at a predetermined point in the movement of the movable member, and means adapted to throw the pin out of active engagement with the shoulder.

23. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, and a cam formed on the casing adapted to throw the pin out of active engagement with the shoulder on further movement of the member.

24. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, means adapted to prevent the pin from taking the right course in the grooves when the combination is not properly operated, and a cam formed on the casing adapted to throw the pin out of active engagement with the shoulder on further movement of the member.

25. In a lock in combination: latch mechanism, a movable member provided with a labyrinth of grooves, a knob and connections adapted to move the member, a link connected to the latch mechanism, a pin on the link engaging with said grooves, a shoulder

formed in said grooves adapted to act on the pin to actuate the latch mechanism when the member is moved a variable predetermined number of times and a variable predetermined distance in opposite directions to lead the pin through the grooves to said shoulder, means adapted to hold the pin against the shoulder when the latter is acting upon it, and a cam formed on the casing adapted to throw the pin out of active engagement with the shoulder on further movement of the member.

26. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, inclines formed in said grooves adapted to prevent the pin from taking the right course in the grooves when the combination is not properly operated, means adapted to hold the pin against the shoulder when the latter is acting upon it, means adapted to hold the pin in the grooves, and a cam formed on the casing adapted to throw the pin out of active engagement with the shoulder on further movement of the member.

35 27. In a lock in combination: latch mechanism, a rotatable disk provided with a labyrinth of grooves, a knob and connections adapted to move the disk, a link connected to the latch mechanism, a pin on the link engaging with said grooves, a shoulder formed in said grooves adapted to act on the pin to actuate the latch mechanism when the disk is rotated a variable predetermined number of times and a variable predetermined distance in opposite directions to lead the pin through the grooves to said shoulder, a lug formed on the casing adapted to hold the pin against the shoulder when the latter acts upon it, a projection on the opposite side of the link adapted to keep the pin in the grooves, a cam formed on the casing and adapted to act on the projection to throw the pin out of active engagement with the shoulder on further rotation of the disk.

55 28. In a lock in combination, latch mechanism, a rotatable disk provided with a labyrinth of grooves, a knob and connections adapted to move the disk, a link connected to the latch mechanism, a pin on the link engaging with said grooves, a shoulder formed in said grooves adapted to act on the pin to actuate the latch mechanism when the disk is rotated a variable predetermined number of times and a variable predetermined distance in opposite directions to lead the pin through

the grooves to said shoulder, a projection on the opposite side of the link adapted to keep the pin in the grooves, a cam formed on the casing and adapted to act on the projection to throw the pin out of active engagement with the shoulder on further rotation of the disk.

29. In a lock in combination, latch mechanism operative at all times from the inside of the door, a rotatable knob and connections, means operative from the inside of the door adapted to render the latch mechanism operative and inoperative from the outside of the door, and means operative by the knob from the outside of the door adapted to render it operative or inoperative from that side of the door.

30. In a lock in combination: latch mechanism, operative at all times from one side of the door, a spindle, two movable members movable thereby and adapted to coact to bring the spindle into and out of operative engagement with the latch mechanism.

31. In a lock in combination, latch mechanism operative at all times from one side of the door, a knob and connections, means adapted to operate the latch mechanism from both sides of the door, means operative from the inside of the door adapted to render the latch mechanism operative and inoperative from the outside of the door, and means operative by the knob on the outside of the door adapted to render the latter operative and inoperative from that side of the door.

32. In a lock in combination, latch mechanism, a knob on one side of the door adapted to operate the latch mechanism at all times from its side of the door, and means operated from said side of the door adapted to render the latch mechanism operative and inoperative from the other side of the door, and means controlled by the rotation of the knob on the other side of the door adapted to render the latch mechanism operative and inoperative at will from its side of the door.

33. In a lock in combination: latch mechanism, a two part rotatable spindle, one member of which is adapted at all times to operate the latch mechanism, means actuated by the opposite spindle member adapted to bring said opposite spindle member into or out of operative relation to the latch mechanism, and means on the other side of the lock adapted to bring into or out of operative relation with said latch mechanism the said opposite spindle member.

34. In a lock in combination: latch mechanism, a two part rotatable spindle, one part of which is, the other of which is not normally adapted to operate the latch mechanism, two movable members actuated by the latter part and adapted to coact to bring said part into operative relation to said latch mechanism.

35. In a lock in combination: latch mechanism operative at all times from the inside of the door, a knob and connections, means operative from the inside of the door adapted to render the latch mechanism operative or inoperative from the outside of the door, and means operative by the outer knob adapted to render the latch mechanism operative or inoperative from the outside of the door.
- 10 36. In a lock in combination: latch mechanism, a two part rotatable spindle, one part of which is, the other of which is not normally adapted to operate said mechanism, a member carried by the latter, and means whereby the member actuates the latch mechanism at a predetermined point in its movement.
- 15 37. In a lock in combination: latch mechanism, a two part rotatable spindle, one part of which is, the other of which is not normally adapted to operate said mechanism, a member carried by the latter, mechanism connecting the member with the latch mechanism, the member being adapted to guide the connecting mechanism to a point where the member is capable of acting upon it to actuate the latch mechanism.
- 20 38. In a lock in combination: latch mechanism, a two part rotatable spindle, one part of which is, the other of which is not normally adapted to operate said mechanism, a member carried by the latter, and means whereby the member when turned a variable predetermined number of times and a variable predetermined distance in opposite directions actuates the latch mechanism at a predetermined point in its movement.
- 25 39. In a lock in combination: latch mechanism, a two part rotatable spindle, one part of which is, the other of which is not normally adapted to operate said mechanism, a member carried by the latter, mechanism connecting the member with the latch mechanism, the member being adapted when turned a variable predetermined number of times and a variable predetermined distance in opposite directions to guide the connecting mechanism to a point where the member is capable of acting upon it to actuate the latch mechanism.
- 35 40. In a lock in combination: latch mechanism, a two part rotatable spindle, one part of which is, the other of which is not normally adapted to operate said mechanism, a member carried by the latter, a link connected to the latch mechanism and in engagement with the member, and means carried by the member adapted to act on the link to actuate the latch mechanism at a predetermined point in the rotation of the member.
- 45 41. In a lock in combination: latch mechanism, a pin carried thereby, a two part rotatable spindle, one part of which is, the other of which is not normally adapted to operate said mechanism, a member carried by the latter, and provided with a labyrinth of grooves, a shoulder formed in said grooves adapted to act on the pin to actuate the latch mechanism when the member is moved a variable predetermined number of times and a variable predetermined distance in opposite directions to lead the pin through the grooves to said shoulder.
- 50 42. In a lock in combination: latch mechanism, a pin carried thereby, a two part rotatable spindle, one part of which is, the other of which is not normally adapted to operate said mechanism, a member carried by the latter and provided with a labyrinth of grooves, a shoulder formed in said grooves adapted to act on the pin to actuate the latch mechanism when the member is moved a variable predetermined number of times and a variable predetermined distance in opposite directions to lead the pin through the grooves to said shoulder, and means adapted to prevent the pin from taking the right course in the grooves when the combination is not properly operated.
- 55 43. In a lock in combination: latch mechanism, a pin carried thereby, a two part rotatable spindle, one part of which is, the other of which is not normally adapted to operate said mechanism, a member carried by the latter and provided with a labyrinth of grooves, a shoulder formed in said grooves adapted to act on the pin to actuate the latch mechanism when the member is moved a variable predetermined number of times and a variable predetermined distance in opposite directions to lead the pin through the grooves to said shoulder, and means adapted to hold the pin against the shoulder when the latter is acting upon it.
- 60 44. In a lock in combination: latch mechanism, a pin carried thereby, a two part rotatable spindle, one part of which is, the other of which is not normally adapted to operate said mechanism, a member carried by the latter and provided with a labyrinth of grooves, a shoulder formed in said grooves adapted to act on the pin to actuate the latch mechanism when the member is moved a variable predetermined number of times and a variable predetermined distance in opposite directions to lead the pin through the grooves to said shoulder, inclines formed in said grooves adapted to prevent the pin from taking the right course in the grooves when the combination is not properly operated, means adapted to hold the pin against the shoulder when the latter is acting upon it, and means adapted to hold the pin in the grooves.
- 65 45. In a lock in combination: latch mechanism, a two part rotatable spindle, one part of which is, the other of which is not normally adapted to operate said mechanism, a disk

carried by the latter and provided with a labyrinth of grooves, a link connected to the latch mechanism, a pin on the link engaging with the grooves, a shoulder formed in the 5 grooves adapted to act on the pin to actuate the latch mechanism when the disk is rotated a variable predetermined number of times and a variable predetermined distance in opposite directions to lead the pin through the 10 grooves to said shoulder, a lug formed on the casing adapted to hold the pin against the shoulder when the latter is acting upon it.

46. In a lock in combination: latch mechanism, a two part rotatable spindle, one part 15 of which is, the other of which is not normally adapted to operate said mechanism, a disk carried by the latter and provided with a labyrinth of grooves, a link connected to the latch mechanism, a pin on the link engaging 20 with the grooves, a shoulder formed in the grooves adapted to act on the pin to actuate the latch mechanism when the disk is rotated a variable predetermined number of times and a variable predetermined distance 25 in opposite directions to lead the pin through the grooves to said shoulder, a lug formed on the casing adapted to hold the pin against the shoulder when the latter is acting upon it, and a projection on the opposite side of the 30 link adapted to contact with the casing to hold the pin in the grooves.

47. In a lock in combination: latch mechanism, a two part rotatable spindle, one part of which is, the other of which is not normally 35 adapted to operate said mechanism, a member carried by the latter provided with a labyrinth of grooves, a link connected to the latch mechanism, a pin on the link in engagement 40 with the grooves, a shoulder formed in said grooves adapted to act on the pin to actuate the latch mechanism when the member is rotated a variable predetermined number 45 of times and a variable predetermined distance in opposite directions to lead the pin through the grooves to said shoulder, and means adapted to throw the pin out of active engagement with the shoulder.

48. In a lock in combination: latch mechanism, a two part rotatable spindle, one part 50 of which is, the other of which is not normally adapted to operate said mechanism, a member carried by the latter provided with a labyrinth of grooves, a link connected to the latch mechanism, a pin on the link in engagement 55 with the grooves, a shoulder formed in said grooves adapted to act on the pin to actuate the latch mechanism when the member is rotated a variable predetermined number of times and a variable predetermined 60 distance in opposite directions to lead the pin through the grooves to said shoulder, and a cam formed on the casing adapted to throw the pin out of active engagement with the shoulder on further rotation of the member.

49. In a lock in combination: latch mechanism, a movable member provided with a labyrinth of grooves, a knob and connections adapted to move the member, a link connected to the latch mechanism, a pin on the link engaging with said grooves, means carried by the movable member adapted to act on the pin to actuate the latch mechanism when the member is moved a variable predetermined number of times and a variable predetermined distance in opposite directions to 70 lead the pin through the grooves to said means, means adapted to prevent the pin from taking the right course in the grooves when the combination is not properly operated, and a cam formed on the casing adapted 75 to throw the pin out of active engagement with the shoulder on further rotation of the member.

50. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined 85 number of times and a variable predetermined distance in opposite directions to lead the pin through the grooves to said shoulder, means adapted to hold the pin against the shoulder when the latter is acting upon it, and a cam formed on the casing adapted to throw the pin out of active engagement with the shoulder on further rotation of the member. 90

51. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined 105 number of times and a variable predetermined distance in opposite directions to lead the pin through the grooves to said shoulder, inclines formed in said grooves adapted to prevent the pin from taking the right course in the grooves when the combination is not properly operated, means adapted to hold the pin against the shoulder when the latter is acting upon it, means adapted to hold the pin in the grooves, and a cam formed on the casing adapted to throw the pin out of active engagement with the shoulder on further rotation of the member. 110

52. In a lock in combination: a casing, latch mechanism, a movable member provided with a labyrinth of grooves, a knob and connections adapted to move the member, a link connected to the latch mechanism, a pin 125

on the link engaging with the grooves, and means for misleading an uninitiated person as the pin moves through the grooves, comprising in part: a post erected on the casing, a 5 link pivoted on the post, a pin on said link adapted to engage with said grooves.

53. In a lock in combination: a casing, latch mechanism, a movable member provided with a labyrinth of tapered grooves, a 10 knob and connections adapted to move the member, a link connected to the latch mechanism, a pin on the link engaging with the grooves, and means for misleading an uninitiated person as the pin moves through the 15 grooves, comprising in part: a post erected on the casing, a link of resilient material pivoted on the post, a pin on said link adapted to engage with said grooves, a projection on the other side of said link adapted to keep 20 the strip and link pin in said grooves, said link being adapted to click its pin as it passes over the high points in the tapers of the grooves.

54. In a lock of the character described: 25 means for determining the operation of the combination comprising a spindle, a disk rotated thereby having a labyrinth of grooves on its face and a series of indents in its edge corresponding to divisions of the labyrinth of 30 grooves, latch mechanism, a pin carried thereby and engaging with the grooves, a post formed on the casing, a pawl pivoted thereon, a lever adapted to operate said pawl, and a spring adapted to actuate the lever to 35 force the end of the pawl into the indents as they present themselves.

55. In a lock of the character described: 40 means for determining the operation of the combination comprising, a spindle, a disk rotated thereby having a labyrinth of grooves on its face and a series of indents on its edge corresponding to divisions of the labyrinth, a 45 latch bolt, a spring tending to thrust the bolt to its locked position, latch arms yoked to said bolt, a roll back operating therewith, a link connected to the roll back, a pin on said link engaging with the grooves of the disk, a post formed on the casing, a pawl pivoted on the post, a lever actuated by the spring and 50 adapted to force the end of the pawl into the indents on the disk as they present themselves.

56. In a lock in combination, latch mechanism, a two part rotatable spindle having 55 the ends of the two parts adapted to engage with each other, means adapted to hold the parts of the spindle normally out of engagement, and automatic means adapted to hold them united when the ends are brought into 60 engagement.

57. In a lock in combination, latch mechanism, a two part rotatable spindle having its ends adapted to engage with each other, a 65 spring adapted to hold the parts normally out of engagement, and automatic means

adapted to hold them united when the ends are brought into engagement.

58. In a lock in combination, latch mechanism, a two part rotatable spindle, one part having an angular recess formed in its inner 70 end, the other part having an angular spring seated member adapted to engage with the recess in the opposite part, a spring adapted to keep the parts normally out of engagement, and automatic means adapted to hold them united when the member is brought into engagement with the recess on the opposite part.

59. In a lock in combination, latch mechanism, a two part rotatable spindle, the outer 80 part of which is provided with an angular recess formed in its inner end, the inner part having an angular spring seated member adapted to engage with the recess on the opposite part, a spring adapted to hold the parts 85 normally out of engagement, a pin carried by the inner part adapted to hold that part united to the outer part when the member is brought into engagement with the recess.

60. In a lock in combination, latch mechanism, a two part rotatable spindle, one part having a recess formed in its inner end, the other part having a member adapted to engage with the recess in the opposite member, a spring adapted to keep the parts normally 95 out of engagement, and automatic means adapted to hold them united when the member is brought into engagement with the recess on the opposite part.

61. In a lock in combination: latch mechanism, a two part rotatable spindle, the outer part of which is provided with a recess formed in its inner end, the inner part of the spindle having a member adapted to engage with the recess on the opposite part, a spring adapted 100 to hold the parts normally out of engagement, a pin carried by the inner part adapted to hold that part united to the outer part when the member is brought into engagement with the recess.

62. In a lock in combination: latch mechanism, a two part rotatable spindle, the outer part thereof having an angular recess formed in its inner end, the inner part having an angular spring-seated member adapted to engage with the recess in the opposite part, a spring adapted to hold the parts normally 105 out of engagement, a pin carried by the inner part, and a grooved knurl piece adapted when the pin is moved from the groove and the knurl piece turned to hold the member in engagement with the recess.

63. In a lock in combination: latch mechanism, a two part rotatable spindle, the outer part thereof having a recess formed in its inner end, the inner part having a member adapted to engage with the recess in the opposite part, a spring adapted to hold the parts normally 110 out of engagement, a pin carried by the inner part, and a grooved knurl 115 piece

piece adapted when the pin is moved from the groove and the knurl piece turned to hold the member in engagement with the recess.

64. In a lock in combination: latch mechanism, comprised in part of a roll back, a collar extension thereof provided with a keyway, a two part rotatable spindle, the outer part of which has an angular recess formed in its inner end, the inner part having a key in permanent engagement with the keyway, an angular spring seated member adapted to engage with the recess in the opposite spindle part, a pin carried by the inner part, a knurl piece, a spring adapted to hold the spindle parts normally out of engagement, a groove formed in the inner end of the knurl piece adapted to receive the pin when the spindle parts are out of engagement, the knurl piece being adapted, when the pin is pushed from the groove and when the knurl is turned, to keep the pin from reentering the groove and the member in engagement with the recess.

65. In a lock in combination: latch mechanism, comprised in part of a roll back, a collar extension thereof provided with a keyway, a two part rotatable spindle, the outer part of which has a recess formed in its inner end, the inner part having a key in permanent engagement with the keyway, a member adapted to engage with the recess in the opposite spindle part, a pin carried by the inner part, a knurl piece, a spring adapted to hold the spindle parts normally out of engagement, a groove formed in the inner end of the knurl piece adapted to receive the pin when the spindle parts are out of engagement, the knurl piece being adapted, when the pin is pushed from the groove and when the knurl is turned, to keep the pin from reentering the groove and the member in engagement with the recess.

66. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, means adapted to prevent the pin from taking the right course in the grooves when the combination is not properly operated, and means adapted to keep the pin in the grooves.

67. In a lock in combination: latch mechanism, a movable member provided with a labyrinth of grooves, a knob and connections adapted to move the member, a link connected to the latch mechanism, a pin on the link engaging with said grooves, a shoulder

formed in said grooves adapted to act on the pin to actuate the latch mechanism when the member is moved a variable predetermined number of times and a variable predetermined distance in opposite directions to lead the pin through the grooves to said shoulder, inclines formed in said grooves adapted to prevent the pin from taking the right course in the grooves when the combination is not properly operated, and means adapted to keep the pin in the grooves.

68. In a lock in combination: latch mechanism, a movable member provided with a labyrinth of grooves, a knob and connections adapted to move the member, a link pivoted on the latch mechanism and connecting the latch mechanism and member, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, and means adapted to keep the pin in the grooves.

69. In a lock in combination: latch mechanism, a rotatable disk provided with a labyrinth of grooves, a knob and connections adapted to move the disk, a link connected to the latch mechanism, a pin on the link engaging with said grooves, a shoulder formed in said grooves adapted to act on the pin to actuate the latch mechanism when the disk is rotated a variable predetermined number of times and a variable predetermined distance in opposite directions to lead the pin through the grooves to said shoulder, and a lug formed on the casing adapted to hold the pin against the shoulder when the latter is acting upon it.

70. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, means adapted to keep the pin in the grooves, and a cam formed on the casing adapted to throw the pin out of active engagement with the shoulder on the further movement of the member.

71. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on

the pin to actuate the latch mechanism when the member is moved a variable predetermined number of times and a variable predetermined distance in opposite directions to lead the pin through the grooves to said shoulder, means adapted to prevent the pin from taking the right course in the grooves when the combination is not properly operated, means adapted to keep the pin in the grooves, and a cam formed on the casing adapted to throw the pin out of active engagement with the shoulder on further movement of the member.

72. In a lock in combination: latch mechanism, a movable member provided with a labyrinth of grooves, a knob and connections adapted to move the member, a link connected to the latch mechanism, a pin on the link engaging with said grooves, a shoulder formed in said grooves adapted to act on the pin to actuate the latch mechanism when the member is moved a variable predetermined number of times and a variable predetermined distance in opposite directions to lead the pin through the grooves to said shoulder, inclines formed in said grooves adapted to prevent the pin from taking the right course in the grooves when the combination is not properly operated, means adapted to keep the pin in the grooves, and a cam formed on the casing adapted to throw the pin out of active engagement with the shoulder on the further movement of the member.

73. In a lock in combination: latch mechanism, a rotatable disk provided with a labyrinth of grooves, a knob and connections adapted to move the disk, a link connected to the latch mechanism, a pin on the link engaging with said grooves, a shoulder formed in said grooves adapted to act on the pin to actuate the latch mechanism when the disk is rotated a variable predetermined number of times and a variable predetermined distance in opposite directions to lead the pin through the grooves to said shoulder, a lug formed on the casing adapted to hold the pin against the shoulder when the latter acts upon it, a cam formed on the casing and adapted to throw the pin out of active engagement with the shoulder on further rotation of the disk.

74. In a lock, a disk provided with a labyrinth of grooves, a link movable thereby, a pin on the link moving in said grooves, and a safety device comprised of a post, a link mounted thereon, and a pin on the link adapted to move in said grooves.

75. In a lock: a disk provided with a labyrinth of grooves, a pin moving in said grooves, a starting point for the pin at one

end of said labyrinth, and a shoulder at the other end of the labyrinth adapted to act on the pin to actuate the latch mechanism, the labyrinth being arranged in such a manner that by rotating the disk a predetermined distance in one direction the pin will be brought from any position in the labyrinth to the starting point, and by rotating the disk a predetermined number of times and a predetermined distance in opposite directions the pin will be brought to the shoulder for operating the latch mechanism.

76. In a combination lock, the combination of a latch mechanism, and a member connected thereto, of a cam having a labyrinth of grooves in which the member travels from a starting point to a shoulder when operated by a certain combination constructed and arranged so that when the cam disk is turned improperly in either direction, the member will be caused to travel from any position which it may occupy in the grooves to the starting point thereof, in less than one revolution of the disk without reversing the motion.

77. In a combination lock, the combination of a latch mechanism, a member connected thereto, a cam disk having a labyrinth of grooves through which the said member is adapted to travel from a starting point to a shoulder when operated by a certain combination, each of the said grooves being connected to the groove in which the starting point is located, and means whereby the member will be forced to take the proper path to bring it to the starting point in less than one revolution of the disk when the latter is turned improperly in either direction without reversing the motion.

78. In a combination lock, a latch mechanism, means for withdrawing the latch, a movable member, having an angular hole, which when turned a predetermined distance in opposite directions a predetermined number of times acts to find the combination and operatively connect itself to the means for withdrawing the latch, an angular spindle, having a knob, removably connected to the lock and adapted to fit in the angular hole of the movable member, for operating the said movable member, whereby the first number of the combination can be changed by removing the spindle from engagement with the angular hole, turning it around, and replacing it again.

Signed at New York city this 24 day of May 1905.
